UNITED STATES PATENT OFFICE.

WILLIAM R. WARREN, OF NEW YORK, N. Y.

CONVEYER FOR GRANULATORS.

No. 895,318.

Specification of Letters Patent.

Patented Aug. 4, 1908.

Application filed August 10, 1907. Serial No. 388,056.

To all whom it may concern:

Be it known that I, WILLIAM R. WARREN, a citizen of the United States, residing at New York, in the county of New York and State of New York, have invented new and useful Improvements in Conveyers for Granulators, of which the following is a specification.

This invention relates to means for collecting and removing to a desired spot the products of a granulator, such as is used for granulating molten slag made in a blast furnace or otherwise.

By means of this invention material is carried in a less compact form than is usual in the ordinary conveyers and is thereby capable of more uniform hydration and aeration.

This invention is set forth in the following specification and claim and illustrated in the annexed drawing in which:—

Figure 1 is a plan view partly in section. Fig. 2 is a side elevation partly in section. Fig. 3 is a section along $\times \times$ Fig. 1.

A granulator such as that described in United States Patent #821609, issued 29 May 1906 to Heinrich Colloseus of Berlin Germany, may be used in producing the granulation. I do not claim any device for granulation proper, but merely for the hydration, aeration and proper handling of the material after the granulation has taken place.

In the drawing is shown a rotary drum a , such as is described in the Colloseus patent above mentioned. Above and below the drum are platform conveyers b and c , which move like a belt and at the sides of the drum are also similar platforms d . These platforms, or movable walls or floors, are made to travel in the same direction as the rotation of the drum, or in the direction of its uppermost point. At the ends of the space inclosed between the four walls, are constructed one or more stationary or movable platforms or walls e . The molten slag or supply is delivered by a conduit f to the drum. The rollers g for the belts can be placed in any varied or desired position for the desired inclination.

The drum as described in the Colloseus patent has a corrugated surface, with longitudinal slits through which an aqueous solution of salt is thrown by a centrifugal force against the pellets of molten slag. As the pellets of slag are thrown from the corrugated surface of the granulator they strike the walls, roof and floor of the granulator housings. With these housings as at present constructed the material collects in considerable masses in different parts of the chamber and cannot be removed with regularity nor can a subsequent process of hydration and aeration be accomplished with definite certainty in ratio to volume. It is for this purpose that one or more of the four walls of the chamber are claimed by me to be an improvement, in that they remove the pellets in a continuous manner. The housing formed by the walls b , c , d , and by the end or ends e , catches the molten pellets thrown from the granulator, and moves them in a direction away from the granulator in a regularly distributed volume to a point where they may be hydrated or aerated, and conveyed to a point from which they may be disposed of as desired.

What I claim is:—

1. In a granulator, a housing formed of movable bottom, top and sides.
2. A granulating drum combined with a housing formed of movable bottom, top and sides, the said bottom, top and sides being made to travel in a direction away from the drum.
3. In a granulator, a frame or suitable support supplied with rollers or wheels made to carry movable top, bottom and sides, such supports and wheels being placed so as to hold the housing parts in the desired position.

In testimony whereof I have hereunto set my hand in the presence of two subscribing witnesses.

WILLIAM R. WARREN.
